(57) **CLAIM**

The design for a satellite TV signal-divider, as shown and described.

DESCRIPTION

FIG. 1 is a perspective view of a satellite TV signal-divider, showing my new design;

FIG. 2 is a left side elevation view thereof; the right side elevation view is a mirror image thereto;

FIG. 3 is a top plan view thereof; the bottom plan view is a mirror image thereto; and,

FIG. 4 is a front elevation view thereof; the rear elevation view is a mirror image thereto.
